UNITED STATES PATENT OFFICE.

CHARLES MORTON BELLAK, OF NEW YORK, N. Y.

CIGARETTE HOLDER.

Application filed June 2, 1927. Serial No. 195,887.

This invention relates to cigar and cigarette holders.

The invention has particular reference to the cigarette holder forming the subject of a copending application of the same applicant Serial No. 158,778 filed January 3rd, 1927, but the invention relates specifically to any type of cigarette holder having a cigarette receiving butt provided with a metal lining.

The invention will be described with particular reference to a cigarette holder of the kind set out in the above mentioned copending application, but it is to be understood that the invention is applicable in greater or lesser degree to other cigarette holders of the kind referred to.

An object of the invention is to provide an accessory or attachment which is designed to obviate the difficulty experienced in ejecting cigarette or cigar ends from holders when these ends are so short that they do not project sufficiently from the holder to be readily grasped.

A further object of the invention is to provide such an attachment of a character which may be easily added to existing types of holders of the kind described.

A still further object of the invention is to provide a device of the kind described of a simple, inexpensive and durable character.

A further object of the invention is to provide an ejector construction which will not interfere with the smoking qualities of the cigarette holder.

A still further object of the invention is to provide an ejector of such a form that it will act as a rest serving to hold a cigarette in said holder out of contact with the surface upon which said cigarette holder might be laid, and also to prevent rolling of the cigarette holder, thereon.

A further feature of the invention is to provide a cigarette holder having a tip furnished with a metal lining carrying corrugations acting to retain the cigarette therein, the surfaces of said corrugations being formed preferably as spiral threads, the projecting surface of which threads may be themselves corrugated.

A still further feature of the invention is to provide a cigarette holder having a tip furnished with means or of a configuration such that cigarettes of varying cross section are equally well retained in said holder

together with means for readily ejecting the end of a smoked cigarette.

Further features of the invention will hereinafter appear and be specifically pointed out in the appended claims.

It is to be understood that the form of the invention hereinafter described is given by way of a preferred embodiment, but that the invention is not limited in any way to such embodiment which is given merely by way of illustrative example, the scope of the invention being defined by the appended claims.

In the accompanying drawings:—

Figure 1 is a side view of the holder constructed according to my copending application #158,778 fitted with the ejector forming the subject-matter of the present invention which is shown in withdrawn position, the stub of a cigarette being shown as falling from the holder.

Figure 2 is a view similar to Figure 1 showing the ejector in its pushed-in position, the cigarette holder being shown as resting on a plane surface such as a table top in order to illustrate the action of the ejector tip in holding the cigarette out of contact with said surface.

Fig. 3 is a view in central section on an enlarged scale showing in detail the manner of mounting the ejector.

Figs. 4 and 5 show methods of mounting providing for spring pressure acting to press the ejector against a slot formed in the metal lining in order to effect an airtight closure thereof. In each case a ring member engaging the end of the cigarette butt being shown in an enlarged view in order to make clear in what way this ring member is mounted on the ejector.

The cigarette holder formed according to my earlier application #158,778, filed January 3rd, 1927 comprises essentially a cigarette receiving tip 1 of diameter tapering from one at the forward edge such as to receive a large size cigarette to an inner diameter adapted to hold a small size cigarette.

The interior of the tip member is provided as has already been proposed with corrugations designed to aid in retaining a cigarette within the tip. In the specific embodiment shown, these corrugations are in the form of a projecting spiral thread, 5, which may be of any desired form as

found most suitable. In order to prevent any tendency of the cigarette to slack back on the threads or projecting grooves 5, I may corrugate the surface of these projections in any suitable way for instance by corrugations in the form of a buttress thread. This thread may conveniently be given a form designed to provide a sharp enough edge to bite into the cigarette without breaking the wrapper thereof.

While this spiral projecting thread is the form preferred by me, it will be obvious that modifications of this form might be found to have advantages under certain 15 conditions, for instance, the spiral might take the form of a groove, in the surface of the tip, the pressure exerted in inserting the cigarette being sufficient to cause the latter to extend into and hold in said 20 grooves.

A feature of the invention lies in the formation of the projecting surfaces of the spirally arranged corrugations which are given a form calculated to aid in retaining 25 the cigarette in the tip by tending to prevent slackening back of the cigarette on said spiral projections. This formation might be effected by corrugating the surfaces or by imparting thereto an outline resembling 30 that of a buttress thread.

The stem 3 of the cigarette holder is preferably made as narrow as possible consistent 35 with the necessary mechanical strength. Preferably the stem is formed of a simple tube of less diameter in a vertical direction than in a horizontal in order to cause a minimum separation of the lips, and in small sizes such as suitable for ladies this would probably be the most satisfactory shape. It 40 will be realized of course that a variety of shapes may be given the stem such for instance as a slow twist of the portion of greater width giving a spiral shape.

Many modifications in the form and construction of the cigarette holder may be 45 made. For instance the cigarette receiving end might be formed of different material from the body. In all cases a thin metal shell 7 may be provided with such corrugations, and be fitted inside an outer cover 50 of different material, or formed in a single piece with the stem portion. This latter construction might provide a very attractive cigarette holder the interior of the portion 55 of the tip being held in the exterior portion by any suitable means in its simplest form the shell could be held in position by the outer edge being rolled around the tip portion of the holder, though in the preferred 60 form as shown in Fig. 3, the shell is a separate piece in which the spiral projecting ridges are formed as for instance by rolling, pressing in a die, or in any other suitable way. This shell may be held in position 65 by its inner end abutting against the

interior of the inner end of the tip, and the forward end being expanded against the forward end of the tip, preferably against a sloped shoulder formed at said forward end of the tip which would serve to reinforce the material of the cigarette holder at that point and enable the shell to be firmly engaged therewith, a binding strip 2 engaging in a groove in the exterior of the cigarette holder, and being turned around the forward end of the cigarette holder, and expanded into engagement with the forward end of the metal shell.

It will be realized that when a cigarette has been engaged in the tip, it is in effect 80 screwed therein, and that should the cigarette be smoked close to the end of the cigarette holder, considerable difficulty might be experienced in dislodging the cigarette end. It is to overcome this difficulty that the 85 ejector device of the present invention has been evolved. This device resembles in general arrangement and purpose ejector devices previously proposed in that it consists of a small member extending from the outside of the cigarette holder into the interior 90 of the cigarette receiving tip, and having a part projecting therefrom engaging behind the cigarette end. The ejector, however, 95 differs from all others known to the applicant in that the exterior surface of the cigarette holder is not marred in any way by carrying any part associated with the ejector or being mutilated by slots or grooves 100 cooperating therewith.

It is further differentiated from any device known to the applicant in that the ejector serves a two-fold purpose, in addition to its ejector function, namely that of supporting the cigarette holder upon any plane 105 surface on which it might be laid so that the lighted cigarette therein is held away from said surface, and also to prevent any tendency of the cigarette holder to roll on such a surface.

The ejector comprises a strip 4 of resilient material ending in a support 6, and at its inner end carrying a ring. The strip 4 may be of any convenient dimensions, that shown in Fig. 3 being relatively thin, but 115 wide enough to act as a closure to a slot 8 in the metal lining of the holder. The strip 4 may be guided in its movement in any suitable way, for instance in a groove formed in the material of the cigarette receiving tip or between guides such as wires soldered on each side of the strip to the outer surface of the metal shell or a slot for the passage 120 of the strip, formed in the binding rim 2 taken in conjunction with the slot 8 might 125 be sufficient to guide the strip.

The slot 8 might be formed so as to avoid cutting through one of the projecting ridges 5, or as shown in Fig. 4 in which the slot 8 cuts such a groove, the groove could be 130

filled with solder at the point of slotting so that the strip could still form an air-tight closure.

In order to obtain such a closure, I prefer 5 to apply pressure to the strip at or adjacent the slot 8 and various methods of obtaining such pressure are shown in the figures.

In Fig. 3, the end of the strip 4 is shown as bent back on itself, and obviously the 10 strip could be bent so that the bent-over portion lies between the strip and the metal shell or between the strip and the material of the holder.

An advantageous construction might be 15 that shown in Fig. 5 in which the strip is shown as provided with a double-ended spring 9 attached at its mid-point to the strip, and engaging at its ends with the material of the cigarette holder, the spring being attached to the strip for instance by the 20 projecting ends of a wire loop, which ends are threaded through holes drilled through the strip and the center portion of the spring, and are burred-over, soldered, or otherwise affixed to said strip.

The member engaging against the cigarette end may be of any suitable form such as that just described, or as in the form shown in Fig. 4, a piece of strip metal is 30 bent into circular form with projecting lugs 10 which are passed through a slot in the strip 4, and bent over and soldered to the under side of said strip.

In order to afford a better engaging surface than is given by the thin edge of the strip, the strip might be partly cut through 35 and flanged back.

The forward end of the strip 4 is formed to provide a rest, for instance of the form 40 shown in Fig. 5 comprising spaced apart feet 12. The rest piece 6 may be stamped integrally with the strip 4 or attached there- to in any convenient manner.

It will be apparent that I have provided 45 a cigarette holder of novel characteristics, in which the projecting grooves with their corrugated surfaces act to securely retain a cigarette end in position in the holder, and in which the possible draw-back of having to 50 eject a short cigarette end from the holder is provided against by the simple, but efficient, ejecting device of this invention.

It will be apparent that no deformation

of the exterior surface of the cigarette holder is present although the ejector is positively guided in its movements, and that an air-tight seal is provided although the metal shell is slotted for the passage of the projecting member or ring. 55

The device can be simply and economically manufactured, and will be durable and efficient in action since the ejecting force is applied in a direct manner. 60

It is again pointed out that the construction described is given merely by way of 65 example, and is in no way limitative of the invention, the scope of which is defined by the appended claims.

I claim—

1. A cigarette holder having a cigarette 70 receiving slotted shell arranged within the cigarette receiving end of the holder formed separately from said cigarette holder and fitted with an ejector device comprising a portion extending to the outside of the 75 holder through the front face of the tip of the cigarette holder and formed to support the holder when laid upon a surface such as a table, the body of said ejector device being positioned between said slotted shell and 80 the inner surface of the forward end of the cigarette holder, and a cigarette engaging portion of said ejector arranged to project through the slot in the shell into the cigarette receiving bore of the slotted shell. 85

2. A cigarette holder as claimed in claim 1 in which resilient means are arranged acting to press the ejecting device against the shell member to cover the slot therein.

3. A cigarette holder as claimed in claim 90 1 in which the cigarette engaging member is formed as a ring adapted to engage behind the cigarette end.

4. A cigarette holder as claimed in claim 1, in which said slotted shell member is provided with spiral corrugations acting to retain a cigarette in position, said corrugations being closed at their ends adjacent the slot in the shell member, retaining corrugations formed in the projecting surface of said spiral corrugations, and resilient means acting 95 to press the ejecting device against the shell members adjacent the slot. 100

In testimony whereof I have affixed my signature.

CHARLES MORTON BELLAK.
